TUBULAR CONDUIT SYSTEM FOR BOILERS AND THE LIKE

Giovanni Rossi, Valle Lomellina, Italy

Application May 10, 1949, Serial No. 92,486

Claims priority, application Italy May 11, 1948

1 Claim. (Cl. 122—360)

This invention relates to tubular conduits and more particularly, to a tubular conduit which may be used in steam boilers, and the like.

In a boiler of high evaporating capacity, unless the boiler is fed with distilled water, the tubular conduits, notably the discharge ones, become rapidly coated with scale. In some cases, the scale can be removed by dissolving it by means of chemical agents in accordance with a patented method of this inventor. However, in boilers which do not receive proper care or where very hard water is used, such a scale is apt to become thoroughly insoluble, and mechanical means are required to remove it.

If scaling is not possible because the tubes are not readily accessible, it becomes necessary to dismantle the boiler and the benefits afforded by a high-output, high-efficiency boiler (in comparison with with less efficient but more accessible ones) are lost. Accessibility, however, can hardly be obtained in modern boilers without altering their basic design. As a matter of fact, the conventional arrangement of the boiler tubes even renders an inspection of the interior of the boiler impossible and does not permit the use of tools to mechanically remove the scale, unless the boiler is disassembled.

Moreover, when certain types of fuel are used, the smoke flues, which are formed by the fire and auxiliary tubes, often contain deposits which cannot be removed by the usual blowing or brushing methods and therefore also require disassembly. It would therefore be of great advantage to design the fire tubes so as to be easily disassembled from, and reassembled with, the auxiliary discharge tubes.

A steam boiler constructed with conduit elements in accordance with the present invention is not subject to the above noted faults. Moreover, such a boiler will be smaller in size than conventional boilers and easier to maintain.

It is an object of the present invention to provide a tubular conduit system wherein the interiors of the respective conduits making up the system are readily accessible for cleaning.

It is another object of the present invention to provide a tubular conduit system of the above-noted character for steam boilers and the like.

It is also an object of the present invention to provide in a tubular conduit system an exceedingly simple means for connecting together a plurality of communicating tubes which extend in a plurality of different directions.

With the above objects in view, the present invention mainly consists of a conduit coupling arrangement comprising, in combination, tubular conduit means adapted to contain a fluid having a lower temperature than the temperature outside of said conduit means, the tubular conduit means including a first set of tubular conduit elements and a second set of tubular conduit elements extending parallel to each other, a first transverse conduit element connecting the conduit elements of the

2

first set of conduit elements and communicating with the same, a second transverse conduit element connecting the conduit elements of the second set of conduit elements and communicating with the same, a pair of tubular conduit members having inner ends abutting each other and outer ends secured to and communicating with the first and second transverse conduit elements, respectively, the first and second transverse conduit elements being each formed with an opening located opposite the respective tubular conduit member associated therewith, a threaded bolt having a head abutting against the second transverse conduit element in the region of the opening thereof, the bolt passing through the openings in the first and second transverse conduit elements and through the conduit members, and a nut member fixedly secured to the first transverse conduit element in the region of the opening in the same and being threadedly engaged by the bolt whereby the tubular conduit members are pressed against each other to establish fluid communicating between the first and second sets of conduit elements through the first and second transverse conduit elements and the pair of tubular conduit members, the bolt being cooled by the fluid passing through the conduit means whereby by heat conduction also the head of said bolt located outside of the tubular conduit means is cooled.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is an elevational view of an embodiment of the conduit coupling system of the present invention in readiness for assembly on a boiler;

Fig. 2 is a sectional view of said device taken on lines 2—2 of Figs. 1 and 3 in the direction of the arrows; and

Fig. 3 is a longitudinal partly sectional view of the device in combination with a boiler.

Referring now specifically to Figures 1 to 3, the conduit coupling arrangement of the present invention consists of a first set of tubular conduit elements 10 and a second set of tubular conduit elements 28, the two sets 10 and 28 extending parallel to each other.

The tubular conduit elements of the first set are fitted with detachable cover 12. Cover 12 covers an opening through which deposits and scale on the inside of the conduit element 10 may be removed.

At the upper end of each tubular conduit 10 there is provided a tubular element which is connected to a header 14 which, in turn, is connected by tubes 15 to either the general header or to the steam separator directly. The removable coupling between header 14 and each of the tubular conduit elements 10 is obtained by means of threaded assemblies which are cooled by circulating water so as to withstand high temperatures. More exactly, the threaded assembly means consists of a bolt whose stem 16 goes through the header 14 and is immersed in the water which circulates through the latter, whereas the threaded portion of said bolt 18 is fitted and locked in a bored element 20 properly positioned between the two tubular conduit elements 10.

The bolt head 22 is provided with a washer 24 and fitted in a nipple 25 which is provided on the side of the header 14 and surrounds the bolt stem 16 as previously stated.

To ensure alignment of the various parts a sleeve 17 is provided.

As bolt 16 is screwed on the bored block 20, the header is tightly coupled with the tubular element of the tubular conduit element 10.

A first transverse conduit element 40 communicates with and connects the conduit elements of the first set of conduit elements 10. The second set of tubular conduit elements 28 are connected, respectively, to an upper pre-header 30 and a second transverse conduit element 32. The transverse element 32 is coupled to the first set of tubular conduit elements 10 by means of a bolt 34 whose stem goes through transverse element 32, conduit members 36, 38 and transverse element 40, the threaded portion of the stem being threaded into a nut member 35, fitted in the same way as the block 20 referred to above.

The bolt 34 is provided with a gasket. As said bolt 34 is tightened, it locks tubular conduit member 36 against tubular conduit member 38. Members 36 and 28 are disposed laterally of the transverse conduit elements 32 and 40, their inner ends abutting each other and their outer ends secured to and communicating with the first and second sets of tubular conduit elements, respectively, which are each formed with an opening located opposite the respective member 38, associated therewith.

Members 36 and 38 are kept aligned by a centering sleeve 42 which also serves to align the locking gasket.

The upper head 30 is connected with the circulation and feeding duct 44 which, in turn, leads to the general header or to the steam separator. Header 30 is provided with detachable covers 45. By removing the covers, access is gained to the header, and it is thus possible to clean both the header and the conduit element 28. Header 30 is connected to pipes 44 by means of bolts 46 whose stems, as stated above, are cooled by the water circulation. Said stems are locked in blocks connected to tube 44. A bottom drain 48 is connected by individual branches 49 to the bottom of tubular conduit 10. Besides providing an outlet by which deposits may be removed from the conduits, said drain permits a properly-shaped tool to be inserted into the conduits in order to remove the scale. The foregoing plainly shows that cleaning and scaling are considerably simplified with the conduits of the present invention, as no disassembly is required and the scraping tool can be thrust into the conduits by merely removing covers 12 and 45. If, in some particular instance, it might be necessary to disconnect the first and second sets of conduit elements 10 and 28 to clean them separately, they can be easily and quickly re-assembled.

The invention furthermore affords a notable simplification in boiler construction, as a vertical tube boiler of the multiple inner flue type can now be constructed by merely piecing together on a closed pattern a given number of elements. In this type of boiler the furnace is centrally disposed and surrounded by the conduits. Arrows in Fig. 3 show the direction followed by the hot gases. After passing through an initial ring-shaped passage 50 between conduits 10 and 28, the gases are conveyed either to a discharge outlet or to a second passage 52 (see Fig. 3) existing between the outer sides of conduits 28 and the boiler outer casing C. Casing C consists of a number of ring-shaped units, each made up of two or more collapsible sections which can be removed without disassembling the other units forming casing C so as to afford easy cleaning of the boiler.

As can be seen in Fig. 3, the passage 52 is connected through a ring-shaped cleft 54 to a header chamber 55 which surrounds the whole casing C. A coupling 56, providing an outlet for exhaust gases, is fitted to header

chamber 55. By this system, the hot gases, besides being evenly distributed along the wall formed by conduits 28, are distributed over almost the full length of the wall.

In order to increase the heat transfer rate, a proper gas turbulence must be obtained. In Fig. 3 such a result is achieved by means of a pipe coil 53 which follows a helicoidal pattern and works as a pre-heater. If necessary, extra fittings similar to the one shown as 53 can be arranged in passage 50 as well, by installing them on special, removable trestles or frames to ensure easy cleaning.

Header chamber 55 is topped by a ring-shaped partition wall 58 providing tightness between passages 50 and 52 and to support an annular part 60 which supports cover 62. The ring-shaped partition wall referred to above may also be used to support a layer of insulating material or a gasket 64 to provide tightness among all the different units which casing C consists of.

I claim:

20. A conduit coupling arrangement comprising, in combination, tubular conduit means adapted to contain a fluid having a lower temperature than the temperature outside of said conduit means, said tubular conduit means including a first set of tubular conduit elements and a second set of tubular conduit elements extending parallel to each other, a first transverse conduit element connecting the conduit elements of said first set of conduit elements and communicating with the same, a second transverse conduit element connecting the conduit elements of said second set of conduit elements and communicating with the same, a pair of tubular conduit members having inner ends abutting each other and outer ends secured to and communicating with said first and second transverse conduit elements, respectively, said first and second transverse conduit elements being each formed with an opening located opposite the respective tubular conduit member associated therewith; a threaded bolt having a head abutting against said second transverse conduit element in the region of said opening thereof, said bolt passing through said openings in said first and second transverse conduit elements and through said conduit members; and a nut member fixedly secured to said first transverse conduit element in the region of said opening in the same and being threadedly engaged by said bolt whereby said tubular conduit members are pressed against each other to establish fluid communication between said first and second sets of conduit elements through said first and second transverse conduit elements and said pair of tubular conduit members, said bolt being cooled by the fluid passing through said conduit means whereby by heat conduction also said head of said bolt located outside of said tubular conduit means is cooled.
